UNITED STATES PATENT OFFICE.

GEORGE I. KING, OF DETROIT, MICHIGAN, ASSIGNOR TO AMERICAN CAR & FOUNDRY COMPANY, OF ST. LOUIS, MISSOURI, A CORPORATION OF NEW JERSEY.

GONDOLA CAR.

No. 895,275.

Specification of Letters Patent.

Patented Aug. 4, 1908.

Application filed September 7, 1901. Serial No. 74,659.

To all whom it may concern:
Be it known that I, GEORGE I. KING, a citizen of the United States, residing at the city of Detroit, county of Wayne, State of Michigan, have invented a certain new and useful Improvement in Gondola Cars, of which the following is a full, clear, and exact description, such as will enable others skilled in the art to which it appertains to make and use the same, reference being had to the accompanying drawings, forming part of this specification, in which—

Figure 1 is a plan view of one end of my improved car; Fig. 2 is a side elevational view thereof; Fig. 3 is a plan view showing the underframing; Fig. 4 is a vertical sectional view through one end of the car; Fig. 5 is a cross sectional view on line 5, 5, Fig. 3; and Fig. 6 is a cross sectional view on line 20 6—6, Fig. 3.

This invention relates to a new and useful improvement in gondola cars, the object being to construct a car employing structural iron or steel in the body and frame-work, to 25 obtain the greatest strength with a minimum amount of material employed.

The invention shown is designed particularly as an improvement upon the gondola car shown in United States Patent No. 30 658,788, granted October 2, 1900, upon an application filed by me.

This present invention consists in the construction, arrangement, and combination of the several parts, all as will hereinafter be 35 described and afterwards pointed out in the claims.

In the drawings 1 indicates the side sheets of the car, which are strengthened by angle-posts 2, 3, and 4, said posts being duplicated 40 at each side of the car and at each end, and consisting preferably of commercially-rolled structures whose cross-section is T-shaped, or two angle-plates are arranged parallel to each other and back to back. These posts 45 are vertically disposed, and the posts 2 extend below the lower edge of the side sheets 1 opposite the ends of the body bolsters 5, to which they are secured by suitable rivets. The posts 3 terminate at the lower edges of 50 the side-sheets 1, while the posts 4 extend some distance below the lower edges of the side sheets and carry cross-beams 6 at their lower ends, which cross-beams, as shown in Fig. 4, are preferably I-shaped in cross-section, and located beneath the framing of the

car, which framing said I-beams support. These I-beams are attached to the lower ends of posts 4 by suitable angle connections 6* and connection-plates 7, which connection-plates are widened at their upper ends to serve as gussets and in this manner greatly strengthen the connection between the post 4, the lower edge of the side sheet, and the cross-beam 6. The side sheets 1 may be further strengthened at their middle portions and at points opposite the doors in the floor by angle-posts 8.

9 indicates an angle secured to the upper edge of the end wall, and 10 are angles attached to the upper edges of the side sheets, said angles 10 being preferably in the form of bulb angles, the bulb flanges thereof being projected horizontally and outwardly and being of substantially triangular form with rounded corners. These angles 10 form the compression flanges of the side walls, which act as plate girders and the side stakes 4 are notched out or shaped at their upper ends to conform to the contour of the bulb flanges of the angles 10.

The length of the car shown in the accompanying drawings in actual practice is designed to be about forty feet, the distance from center to center of the trucks being about thirty feet. This distance, thirty feet, is divided into three equal parts, forming panels, each of which has a span of about ten feet, said panels being defined by the posts 2, which form a most rigid support by being secured to the bolsters 5 and the posts 4, which carry the cross supporting beams 6.

12 indicates the end sheet or end wall. Corner-posts 16 are arranged externally the side and end sheets, being secured thereto by suitable rivets, said corner-posts extending down to the lower edges of said sheets and riveted to the end sills 17. The lower edges of the end sheets are also riveted to these end sills, as shown in Fig. 3. The usual hand-holds or rods for the train-crew are provided on the end sheets, and steps may also be employed on the inner faces of the sheets to form foot-holds when the car is empty.

18 indicates an angle attached to the lower face of the side sheet for supporting the floor-sheets, which floor-sheets are riveted thereto along their side edges. These angles 18, in addition to forming an attaching medium for the floor-sheets, also act as tension flanges for the side-sheets; and said angles

18 also serve as light side sills by resisting the buffing and pulling stresses at the sides of the car.

19 The body bolster 5 is preferably in the form of an I-beam, and extends continuously from side to side of the car. This bolster is reinforced by a bottom cover plate 24 (to which are attached the center and side bearings), and a top cover plate 22, said cover plate extending, preferably, nearly to the ends of the I-beam.

20 21 indicates the draft sills, preferably I-shaped in section, which are attached to the end sill 17, by suitable connection plates, the top and bottom flanges thereof being riveted to the bolster cover plates, while connection plates are riveted to the webs thereof, and of the I-beam 5, to complete the connection.

21^a indicates diverging center sills which are preferably in the form of channels having their flanges presented inwardly or toward each other. These center sills while being interrupted as hereinafter described, extend from bolster to bolster, they occupying the position of intermediate sills at the middle section of the car. The ends of these sills adjacent the bolster are attached to flanged splice plates 21^b whose flanges are riveted to the top and bottom cover plates, and whose web is riveted to the flanged connection plate 21^c, riveted to the web of the I-beam 5 and to the top and bottom plates.

22 By referring to Fig. 4, it will be observed that the draft sills 21, by reason of the connections above described, are depressed below the floor line, while the diverging center sills 21^a have their top flanges flush with the top cover plate 22. The center sills 21^a make efficient floor supports in conjunction with the top cover plate, and in this manner the floor plates are supported by the bolster covers, the center sills, and diagonals. One advantage of this construction is the use of short independent draft sills. The metal underframe is complete in itself, and is not dependent upon the floor sheets for much strength. A level floor without projections or protuberances thereon is rendered possible by this construction, which would not be the case if the bolster cover was placed directly upon the floor, or rested on top of the sills as is commonly done, wherein the floor sheets have to be crimped over said cover plates.

23 24 indicates corner connection plates secured, respectively, to the angles 18 and to inwardly extending shelves 25 projecting from the end sill 17. Diagonal angle-braces 26 extend from the corner connection-plates 24 to the cover plate 22 of the bolster, said braces being crimped to support the floor sheets.

25 27 indicates connection-plates secured to the angles 18 and at points preferably in line with the posts 3. Diagonal angle-braces 28 are connected to these connection plates 27

and to the cover plate 22, said braces being crimped to support the floor sheets. Floor beams 29 are riveted to the connection-plates 27 and to the sills 21^a, these floor-beams also serving as splice-plates for the abutting ends of the floor-sheets. Diagonal braces 30 are attached to the connection-plates 27 and to the floor-sheets, said braces extending in the direction of points of connection between the sills 21^a and 23.

31 indicates the end floor-sheet, which serves as a cover-plate for the members of the underframing immediately therebeneath, including the draft sills, which members are attached to said floor-sheet by suitable rivets, as shown in Fig. 1. The end of the floor-sheet 31 referred to terminates over the continuous bolster 5 and is riveted to one flange thereof through the top cover plate. The next adjacent floor-sheet 32 is riveted to the other top flange of the body bolster, (through the cover plate 22), forming a butt-joint with the sheet 31. Floor-sheet 32 also serves as a cover-plate for the members of the underframing immediately therebeneath, which are riveted thereto, and this floor-sheet 32 terminates above the floor-beams 29, as shown in Fig. 1. The next adjacent floor-sheet 33 is also riveted to the floor-beams 29, whereby a butt-joint is formed therebetween and the sheet 32. This floor-sheet also serves as a cover-plate for the members of the underframing therebeneath and its inner edge terminates above the channel 34 arranged between, and attached to, the sills 23 near their outer ends. This channel 34 serves as the end wall of the exit opening for the load and is preferably co-extensive in depth with the channels 23, whereby the doors which close the exit opening for the load will find a bearing against the bottom flanges of the sills 23 and this short cross-sill 34 (see Fig. 6).

35 indicates the side floor-sheets, which are attached to the sills 23 and the angles 18, said side floor-sheets being practically co-extensive in length with the door opening.

36 indicates hinge-lugs attached to the channels 23, to which the doors 37 are secured. These doors open downwardly and outwardly in opposite directions and are controlled by the chain 38 passing over suitable sheaves and around a drum 39, as usual.

While I have shown and described commercially rolled structures of certain cross-sections, it is obvious that other forms may be used, and, therefore, I do not wish to be understood as limiting myself to the particular forms shown and described herein, except as such restrictions may be expressly imposed in the claims.

In a companion application filed by me August 10, 1901, Serial No. 71,549 (patented October 29, 1901, No. 685,451) I have illustrated a construction of underframe in which continuous flanged bolster elements extend

from side sill to side sill, the center sills extend from bolster to bolster, and flanged draft sills extend from the bolsters to the end sills, the bolster elements being provided with an overhanging top cover plate in the plane of the draft rigging and riveted to the top flanges of said bolster elements, said center sills and said draft sills. I did not in my said companion application claim this combination of elements but do claim the same here.

Having thus described my invention, what I claim and desire to secure by Letters Patent is:—

1. In a car, the combination with a body portion comprising metallic floor, side, and end sheets, of continuous body bolsters extending from side to side of the car, posts arranged externally the side sheets and secured to the ends of the body bolsters, and diagonal braces 26 extending from the corners of the car inwardly, said braces being attached to the end floor-sheet; substantially as described.

2. In a car, the combination with the body portion comprising metallic floor, side and end sheets, of a bolster continuous from side to side of the car, side sills, draft sills, end sills, and diverging center sills, said floor sheets being attached to all of said parts; substantially as described.

3. In a car, the combination with the body portion comprising metallic floor, side, and end sheets, of a bolster continuous from side to side of the car, draft sills, end sills, diverging center sills, and diagonal bracing, said bracing, center and draft sills being attached to the floor-sheets; substantially as described.

4. In a car, the combination with side walls in the form of plate girders, of side sills attached to the lower edges of said side walls and serving as tension flanges for the plate girders, end sills, body bolsters continuous from side to side of the car, draft sills extending from the body bolsters to the end sills, and floor-sheets attached to the above mentioned members of the under-framing; substantially as described.

5. In a car, the combination with side walls in the form of plate girders, of side sills attached to the lower edges of said side walls and serving as tension flanges for the plate girders, end sills, continuous body bolsters, draft sills extending from the bolsters to the end sills, diverging center sills whose middle sections are parallel to each other, diagonal bracing, and floor-sheets riveted to the members of the underframing and serving as a cover-plate therefor; substantially as described.

6. In a car, the combination with the body portion comprising metallic floor, side, and end sheets, of posts 3 arranged externally the side sheets, connection-plates secured to the side-sheets opposite the posts, and diagonal

bracing secured to said connection-plates and to the floor-sheets; substantially as described.

7. In a car, the combination with the body portion comprising metallic floor, side, and end sheets, of center sills extending longitudinally the body portion, posts secured to the side-sheets and extending below the plane of the center sills, cross-beams arranged between and secured to the depending ends of said posts, said cross-beams being arranged under the center sills, connection-plates 7 attached to the side sheets for strengthening the depending ends of said posts, and body bolsters for supporting the side-sheets and center sills; substantially as described.

8. In a car, the combination with the body portion comprising metallic floor, side, and end sheets, of posts 4 arranged externally the side-sheets and extending below the lower edges thereof, sills for supporting the floor-sheets, said floor-sheets being attached thereto and serving as a cover-plate therefor, cross-beams arranged under said sills for supporting the same, said beams being attached to the lower ends of said posts, and connection-plates attached to the side-sheets and to the lower ends of the posts for strengthening the latter and assisting in supporting said cross-beams; substantially as described.

9. The combination with the side-sheet, of an angle 18 secured to the lower edge thereof and flush with the top surface of the underframing of the car, floor-sheets attached to said angle and to the underframing; substantially as described.

10. The combination with a car body, of body bolsters continuous from side to side of the car, end sills, draft sills extending between the end sills and body bolsters, sills 21^a extending from the body bolsters inwardly, and sills 23 attached to the innerends of said sills 21^a; substantially as described.

11. The combination with a car body, of body bolsters continuous from side to side thereof, and sectional sills, the middle sections of said sills being parallel throughout their lengths in the middle portion of the car, the intermediate sections converging toward each other as they approach the body bolsters, to which they are attached, and the outer or end section being parallel to each other and forming supports for the draft-rigging; substantially as described.

12. The combination with a car body, of continuous body bolsters extending from side to side thereof, cross beams arranged transversely the car and suspended from the car sides, channel-beam sills arranged under the car body and in the plane of the body bolsters, said sills being composed of sections joined together, the joints occurring over the cross beams, and independent draft sills attached to the continuous body bolsters; substantially as described.

13. A car provided with a body bolster, a top cover plate connected to said bolster and projecting laterally beyond the sides thereof, a flanged center sill having its upper flange 5 extending flush with the top face of said cover plate, and means for securing said center sill to the bolster; substantially as described. 73
14. The combination with a bolster, and its top cover plate, of a center sill member 10 whose top flange is flush with the top of the cover plate, a connection plate attached to the bolster, and a splice plate connecting the center sill member and the said connection plate; substantially as described. 75
15. 15. The combination with a bolster, having top and bottom cover plates, of a flange connection plate attached to said parts, a splice plate attached to said cover plates and to said connection plate, and a center sill 20 member attached to said splice plate; substantially as described. 80
16. The combination with an end sill, of a body bolster continuous from side to side of the car, flanged draft sills extending between 25 and attached to the end sill and body bolster, a flanged center sill member whose top flange is on a plane above the plane of the flanges of the draft sills, and means for attaching said center sill member to the body bolster; substantially as described. 85
17. The combination with an end sill, of a body bolster continuous from side to side of a car, cover plates for said bolster, draft sills extending between the end sill and body bolster, said draft sills being attached to said 35 parts and the top and bottom cover plates, the depth of said draft sills being substantially co-incident with the depth of the body bolster, a flanged center sill member, whose top flange is flush with the upper surface 40 of the top cover plate, and connection and splice plates for attaching said center sill member to the body bolster; substantially as described. 90
18. The combination with a body bolster and its top cover plate, of a flanged center sill member whose top flange is flush with the upper surface of the top cover plate, an end sill, depressed draft sills extending between 45 the end sill and body bolster, and diagonal braces which are flush with the top cover plate of the bolster; substantially as described. 95
19. The combination with an underframing, including a body bolster, top cover plate 50 for said bolster, diagonal braces, center sills and floor beams, of floor sheets arranged upon and attached to said parts, the contiguous ends of said floor sheets forming butt joints; substantially as described. 105
20. In a car, the combination with an under-framing, including a body bolster continuous from side to side of a car, centersills, transversely arranged floor beams, of floor sheets 55 31, 32, 33 and 35 attached to said parts, the contiguous edges of said floor sheets forming butt joints; substantially as described. 110
21. In an underframe for cars, the combination with a continuous flanged bolster extending from side sill to side sill, flanged center sills and flanged draft sills, a top cover plate riveted to the upper flanges of the bolster and extending on each side thereof and riveted to the upper flanges of the draft sills, a bottom cover plate likewise riveted to the 75 bottom flanges of the bolster and draft sills at their junction points, and means for connecting the center sills to the bolster; substantially as described. 115
22. The combination with end and side 80 sills, of continuous body bolsters extending from side sill to side sill and secured thereto, top and bottom cover plates for said bolsters, which extend approximately to the ends of the bolsters, and are widest in substantially the plane of the draft rigging, diagonal braces extending from the junction of the end and side sills inwardly and in converging lines, the inner ends thereof being attached to the top cover plate of the bolster, connection 90 plates at the junction of the end and side sills, to which the outer ends of said diagonal braces are connected, and a floor sheet attached to the side-sill, the top cover plate of the bolster, and to said diagonal braces; substantially as described. 95
23. A metallic railway-car comprising side walls, stakes secured thereto, transverse floor-supports, and connecting and reinforcing members secured to the side walls and to 105 the floor-supports and having the lower ends of the stakes riveted thereto. 100
24. In a railway car, a plate girder side having vertical stiffening members, a top 110 guard angle forming a compression flange and secured to the upper edge of the car side by one of its legs, the other leg standing outwardly, and means for strengthening and reinforcing the outer edge of said outstanding leg; substantially as described. 115
25. In a railway car, the combination with the car side and the vertical stiffening members or stakes thereof, of a flanged bar or top guard angle secured to the upper edge of said car side and stakes aforesaid, and provided with a bulb or reinforcement integral with its outstanding edge. 120
26. The combination with a car side and the vertical stiffening member or stakes thereof, of a flanged bar or top guard angle, one leg of which is secured to the inner side of the upper edge of said car side and to said stakes, and having an outwardly projecting leg provided with an integral bulb or thickening on the exterior edge thereof. 125
27. In a railway car, a flanged bar or angle of special form, one leg of which is plain and attached vertically to the inside of the upper edge of the car side, the other leg extending horizontally outwards and reinforced or pro- 130

vided with a bulb on the lower side of its outer edge, car stakes attached to the car sides and having their upper ends bent or formed to fit the general inner contour of said 5 reinforced member and bearing against same, and means for securing said top guard angle and stakes to the car side.

In testimony whereof, I hereunto affix my signature, in the presence of two witnesses, this third day of September 1901.

GEORGE I. KING.
